DESIGN FOR A FOOD MIXER

Mortimer R. Anstice, Rochester, and James D. Clague, Livonia, N. Y., assignors to Josiah Anstice & Company, Inc., Rochester, N. Y., a corporation of New York

Application August 12, 1939, Serial No. 86,632

Term of patent 14 years

To all whom it may concern:

Be it known that we, Mortimer R. Anstice, a citizen of the United States, residing at Rochester, N. Y., and James D. Clague, a citizen of the United States, residing at Livonia, N. Y., have invented a new, original, and ornamental Design for a Food Mixer, of which the following is a specification, reference being had therein to the accompanying drawing, forming part thereof.

In the drawing:

Figure 1 is a perspective view of a food mixer, showing our new design; and

Figure 2 is a top plan view thereof, the bowl element being eliminated.

The dominant feature of the design resides in the portion shown in full lines in the drawing.

We claim:

The ornamental design for a food mixer, as shown and described.

MORTIMER R. ANSTICE.
JAMES D. CLAGUE.
